DESIGN FOR AN ANIMAL TOY

Clara M. Flandermeier, Milwaukee, Wis.

Application September 23, 1944, Serial No. 115,422

Term of patent 3½ years

(Cl. D34—2)

To all whom it may concern:

Be it known that I, Clara M. Flandermeier, a citizen of the United States, residing at Milwaukee, in the county of Milwaukee and State of Wisconsin, have invented a new, original, and ornamental Design for Animal Toys, of which the following is a specification, reference being had to the accompanying drawing, forming part thereof.

In the drawing,
Fig. 1 is a side perspective view of an animal toy embodying my new design.

Fig. 2 is a front view thereof in perspective.

I claim:

The ornamental design for an animal toy, as shown.

CLARA M. FLANDERMEYER.
